UNITED STATES PATENT OFFICE

95,577

DESIGN FOR A CONSOLE HEATER

Phil Brinckerhoff, Los Angeles, Calif., assignor
to Payne Furnace & Supply Company, Inc., Beverly Hills, Calif., a corporation of California

Application March 5, 1935, Serial No. 55,733

Term of patent 7 years

To all whom it may concern:

Be it known that I, Phil Brinckerhoff, a citizen of the United States, residing at Los Angeles,
in the county of Los Angeles, State of California,
have invented a new, original, and ornamental Design for a Console Heater, of which the following is a specification, reference being had to the accompanying drawing, forming part thereof.

The figure is a perspective view showing my new design.

I claim:

The ornamental design for a console heater substantially as shown.

PHIL BRINCKERHOFF.
